TOY BED

Alice E. Wilder, Oakland, Calif.

Application March 28, 1932, Serial No. 601,484
Renewed February 19, 1934

13 Claims. (Cl. 46—37)

This invention relates to toy beds and has for its objects a construction in such beds whereby portions of the bed may be folded to facilitate shipment thereof and by which construction certain parts of the bed ordinarily susceptible to breakage are practically free from that danger without altering the appearance of the bed.

These and other objects are attained by the means described herein and disclosed in the accompanying drawing, in which:

Fig. 1 is a perspective view of a bed as set up for use.

Fig. 2 is an enlarged fragmentary elevation of a portion of the bed embodying my invention, with a part broken away to disclose the detailed structure thereof.

Fig. 3 is a view taken along the line 3—3 of Fig. 2.

In detail, the bed comprises a head board 1, and a foot board 2 of the bed frame, with legs 3 secured at opposite ends thereof respectively and the head and foot boards including the legs attached thereto connected in the ordinary manner as by side rails extending between the legs at the head and foot of the bed respectively (not shown) forming a rectangular bed frame for supporting a mattress, as indicated at 4. The head and foot boards are secured at opposite ends respectively to the upper ends of the legs by mortice and tenon joints as indicated in Fig. 2, the upper ends of the legs extending slightly above the upper edge of the boards as clearly indicated in Fig. 2. The upper end of each of the legs has rounded edges 5 and a flattened end 6 and is provided with a vertical hole 7 drilled into the end of the leg longitudinally thereof in the center of the flattened portion.

On the upper ends of each of the legs posts 8 are provided in upward extension of the legs to make a bed commonly called a poster bed. These posts are centrally flattened at their lower ends each, as indicated in Fig. 2, to seat against on the flattened upper ends of the legs respectively and are rounded at the edges of the lower end at 9. A hole 10 is drilled in the lower end to axially align in upward extension with the hole 7 in the leg. The posts 8 are each secured to the legs by a coil spring 11 extending at its opposite ends respectively into holes 7 and 10. This spring is first secured at its upper end in the upper end of hole 10 as by a pin 12 and is then pulled into the hole 7 in the leg through a mortice 13 in the upper end of the leg in which the tenon at the end of the foot or head board, as the case may be, is later inserted. By this means the spring 11 is tensioned and is then fastened at the lower end in the lower end of hole 7 by a staple or pin 14.

It will be seen from the foregoing, that the posts 8 will be held in upright position by the tension of the spring 11 with the flattened upper

ends of the legs and the flattened lower ends of the posts seated firmly together, and to all appearances the posts and legs being a unitary structure. Also, it will be manifest that the posts cannot be broken off by being accidentally struck, due to the fact that the posts will give in any direction when struck, and will afterward automatically resume an upright position the same as before, the rounded adjacent ends of the posts and legs acting as a universal bearing at the joint.

It is customary in the trade to make toy beds in sets of several sizes to accommodate "families" of dolls, as it were, and these are packed in sets. Formerly, in order to make up these sets, it has been necessary to ship the beds "knocked down", or to hinge the foot and head pieces, including the legs, to the frame. Where the beds are shipped knocked down, the retail stores are compelled to set up the beds, work which is objectionable to the stores since it takes time, and frequently the parts are damaged due to inexperienced help or are soiled, or the parts do not properly fit, etc., and where the foot and head pieces are hinged, the mechanical structure is too complicated for the child to properly operate involving friction joints with no positive catch, or catches which become bent or broken, all in all being unsatisfactory for use by children.

In my structure this is overcome by providing means for holding the posts in depressed position in which position the smaller beds in the set may be nested below the larger ones, and make a package.

The means for holding the posts in depressed position comprise foot and head members 15 being flat pieces extending longitudinally of the foot and head boards 1 and each grooved on the lower edge at 17 to fit over the upper edges of the foot and head boards respectively. These pieces may be secured to the boards by gluing in the groove or any desirable manner.

At their opposite ends the lower corners of the pieces 15 are cut away thus forming overhanging ends 18 which are concave on their undersides as at 19 and the pieces are of a length so that when the posts 8 are folded downwardly over the ends of the foot and head boards, the outer upper ends of the posts will pass under the overhanging ends of the pieces 15 and will fit in the concave portion 19 and will be held therein as indicated in dotted lines in Fig. 2.

In order to release the posts from this position it is only necessary to push the ends of the posts from engagement under the ends 18 of the pieces 15 and the posts will automatically resume an upright position.

The foot and head pieces 15 are slightly higher at their upper edges than the upper sides of the posts when the posts are in depressed position

in order to prevent accidental dislodgement of the posts in nesting the beds or in sliding the beds under some piece of furniture in a child's playroom so as to be out of the way, since the 5 foot and head pieces 15 will take any pressure or blow imposed thereon and not the posts.

It is manifest of course that the foot and head pieces 15 may be made in ornamental designs as they complement the design of the bed, and 10 the posts may be long or short as desired, the length of the pieces 15 being correspondingly lengthened or shortened. Also the posts may take many ornamental shapes as may be accomplished by turning on a lathe or otherwise; and 15 when folded will make a differently designed bed than when upright thus affording two distinct kinds of beds both ornamental and complete.

Having described my invention, I claim:

1. A bedstead provided with posts at the corners thereof projecting upwardly therefrom, said 20 posts being mounted for movement from upright to a substantially horizontal position, and means arranged and adapted to yieldably urge said posts from a substantially horizontal to an upright position and to yieldably retain said posts in upright position.

2. In a toy bedstead including legs for supporting the bedstead on the floor, posts positioned on said legs in upward extension thereof, 30 each of said posts and legs provided with axially aligned openings at their adjoining ends, and a coil spring within said openings secured at one end within the opening in the post and at the other end within the opening in the leg, said 35 spring being under tension whereby the post is yieldably retained in upward extension relative to the leg.

3. In a structure as defined in claim 2, the post and leg each being formed with a flat surface 40 around said openings respectively for firmly seating together when the post is in upright position; and the edges of the adjoining ends of the post and leg being rounded to permit rocking the post in any direction.

4. A bedstead provided with posts at the corners thereof projecting upwardly therefrom, means mounting the posts each at their lower ends to the bedstead for movement of the posts 50 to a laterally extending position, and means for securing the posts in the laterally extending position, said means comprising a member on the bedstead adapted to engage the posts when in the last mentioned position.

5. In a toy bedstead including legs for supporting the bedstead on the floor, a post on each of 55 said legs positioned in upward extension thereof and means for yieldably retaining said post in upright position, said means arranged and adapted to secure the post to the leg and to permit movement of the post to a laterally extending position, and means on a side of the bedstead arranged and adapted to engage the post for holding the same in said last mentioned position.

6. In a toy bedstead including legs for supporting the bedstead on the floor, a post on each of 60 said legs positioned in upward extension thereof and means yieldably retaining said post in upright position, said means arranged and adapted to secure the post to the leg and to permit movement of the post to a laterally extending position, and means on a side of the bedstead arranged and

adapted each to engage the outer ends of a pair of said posts for holding the posts in the last mentioned position.

7. In a structure as defined in claim 6, said 80 means comprising a horizontally disposed member disposed above a side of the bedstead and secured thereto intermediate its ends, the ends of said member being undercut and recessed on the underside of said ends to provide a socket for receiving the ends of each of the pair of posts respectively.

8. A toy bedstead including a head board and a foot board and legs at the opposite ends thereof for supporting the bedstead on the floor, posts positioned on said legs in upward extension thereof, means mounting the posts thereto for movement from an upright to a laterally extending relation while retaining the adjacent ends of the posts and legs respectively in abutting relation, means yieldably retaining the posts in upright position, and means on the head board and foot board arranged and adapted to engage an end each of the posts at the head and foot of the bed respectively for holding said posts in laterally extending position.

9. In an article of furniture of the type having a main body portion and a post projecting therefrom, means yieldably retaining said post in a position substantially perpendicular to the body portion and securing the post thereto with its 105 inner end seated against the body portion and means permitting movement of the outer end of said post in any direction about the point of contact of the inner end with the body as an axis.

10. A bedstead provided with posts at the corners thereof projecting upwardly therefrom, said 110 posts being mounted for movement from upright to a substantially horizontal position, means yieldably retaining said posts in upright position and means for securing said posts in horizontal position.

11. In an article of furniture having a main body portion, a member normally projecting outwardly therefrom and pivotally secured thereto at the end adjacent the body portion for movement of the member from the normal outwardly projecting position to a laterally extending position at either opposite side, means arranged and adapted to yieldably urge said member from the last mentioned position to the normal outwardly projecting position at all times.

12. In a toy bedstead including legs rigidly secured thereto for supporting the bedstead on the floor, posts positioned on the legs in upward extension thereof and means yieldably retaining 130 said posts in upright position, said means comprising a resilient member secured at opposite ends respectively to and extending at opposite ends into each of said posts and legs respectively.

13. In a toy bedstead including legs rigidly secured thereto for supporting the bedstead on the floor, posts positioned on the legs in upward extension thereof and means yieldably retaining 135 said posts in upright position, each of said posts and legs provided with axially aligned openings at their adjoining ends and said means comprising a resilient member positioned within the openings and extending across the juncture of the adjoining ends of the post and leg and secured at opposite ends to the post and leg respectively.

ALICE E. WILDER.
